(57) CLAIM

We claim the ornamental design for a microwave-safe glass lid, substantially as shown and described.

DESCRIPTION

FIG. 1 is a perspective view of a microwave-safe lid in accordance with the present design;

FIG. 2 is a front view of the microwave-safe lid shown in FIG. 1;

FIG. 3 is a side view of the microwave-safe lid shown in FIG. 1;

FIG. 4 is a top view of the microwave-safe lid shown in FIG. 1; and,

FIG. 5 is a bottom view of the microwave-safe lid shown in FIG. 1.
